UNITED STATES PATENT OFFICE

DANIEL C. HINDS, OF SIOUX FALLS, SOUTH DAKOTA, ASSIGNOR TO RYAN MANUFACTURING CORPORATION, OF CHICAGO, ILLINOIS, A CORPORATION OF ILLINOIS

ROAD GRADER

Application filed January 30, 1924. Serial No. 689,416.

My invention relates to road graders, and has to do more particularly with machines of this character adapted for road grading and working upon the ditches and banks along- 5 side the road, an object being to provide an improved machine of this character.

There are a number of features to my invention, among which is the provision of a machine having an improved leveling or tilt- 10 ing main frame; another feature is the provi- 15 sion of such a frame in combination with tilt- 20 ing wheels, whereby certain advantages hereinafter more particularly pointed out are secured; another feature is a transversely shift- 25 able mould board frame further amplified by the provision of vertical adjustment to 30 the draw-bar of the mould board frame with side tilting of the mould board circle, giving a four-point adjustment or pitch to the mould 35 board; another feature is the combination of 40 the tilting wheels, leveling frame and trans- 45 versely shiftable mould board frame, whereby 50 certain advantages in operation are secured; another feature is the combination of the tilt- 55 ing wheel, leveling frame, transversely shift- 60 able mould board frame and four-point mould 65 board adjustment, whereby certain advan- 70 tages in operation are secured; another feature 75 is the provision of a longitudinally adjustable 80 mould board; another feature is the improved 85 mechanism for tilting the wheels; and a 90 further feature is the provision of a rotary 95 disk at the end of the mould board and in alignment therewith, which gives certain ad- 100 vantages in operation.

Another feature of my invention is the pro- 40 vision of a main frame construction in which the mould board mechanism is supported be- 45 tween the outer frame members to permit adjustment of the mould board independent of the frame and wheels.

There are other features in construction, combination and resultant operation, some of 45 which will be hereinafter referred to.

For a better understanding of my inven- 50 tion, reference is to be had to the accompany- 55 ing drawings, in which—

Fig. 1 is a side elevation of the road grader 55 of my invention with parts thereof in section

to more clearly bring out the detailed construction;

Fig. 1^a is a detail view of the mould board draw-bar suspension for vertical adjustment thereof;

Fig. 2 is a top plan view of Fig. 1;

Fig. 3 is a rear view of the rear wheels with part of the mechanism broken away and showing more in detail the rear wheel tilting mechanism and main frame leveling or tilt- 60 ing mechanism;

Fig. 4 is a front view in section along the line 4—4 of Fig. 1 of the front wheels and tilt- 55 ing mechanism thereof;

Fig. 5 is a sectional view along the line 5—5 of Fig. 4, showing more in detail the rack and pinion adjustment for tilting the front 65 wheels;

Fig. 6 is a top plan view of the mould board circle frame and mechanism for rotary adjust- 70 ment thereof; and

Fig. 7 is a detail view in section along the line 7—7 of Fig. 1, showing more particularly the vertical and transverse adjusting mechanism of the mould board circle.

Referring now more in detail to the preferred form of my invention as illustrated herein, I provide a main frame comprising side members 10—11 extending across the rear by section 12 and bent downwardly as 80 indicated in Fig. 1 with a rear pivot shaft 13 to permit tilting or leveling of the frame. The front end of the frame is connected by cross pieces 14—15 pivotally connected to the head 16 by pivot pins 17—18. The main 85 frame is rounded upwardly toward the center so as to provide sufficient clearance for proper adjustment of the mould board and suspending apparatus, and said frame is also preferably widened throughout its center suf- 90 ficiently to permit suitable transverse adjust- 95 ment of the mould board and suspending apparatus relative to the wheels with the transverse adjustment of the main frame relative to the wheels.

The mould board is preferably suspended between the side rails of the main frame and has rotary adjustment, vertical adjustment, and a universal tilting adjustment of the supporting frame. The mould board itself con- 100

sists of a suitable elongated transversely curved member 19 of suitable material, preferably sheet steel, and has strengthening ribs 20 connected by rods 22 removably held by set screws 21 and slidably carried in the supports 23—24 attached to the rotatable member 25 of the supporting circle, which member 25 is slidably rotatably on circle member 27, which latter member is adjustably suspended for movement in various directions. The mould board 19 is thus longitudinally adjustable in its supporting frame, and may be held at any desired position by the set screws 26.

Mould board 19 may be supported upon the opposite side of brackets 23 which are concaved at 23^a so that the board may be carried substantially parallel to and upon the left side of the grader. This permits cleaning out ditches alongside the road and scraping the refuse toward the fence and thus away from the road.

In order to secure a more effective and easier operation of the mould board under certain conditions, I provide a disk wheel 96 acting as an extension of the mould board, and the face of which is in pivotal alignment with the face of the mould board. This disk is rotatably supported on the end of an arm 97 pivotally connected at 98 to the mould board bracket 21 so that the disk may be raised or adjusted into various operating positions, or raised above the mould board out of operating position. A suitable bracing is supplied for holding the disk in its adjustment and against operating strain, and to this end a rod 99 extends into the tube 100 pivoted at 101. The parts 99 and 100 hold the disk 96 in adjustment by means of a pin 102 adapted to be inserted in the proper hole of a series extending along through the bar 99. Among other advantages this disk may be adjusted in advance of the mould board when operating upon heavy banks or cutting heavy roads, the disk relieving the strain otherwise placed upon the end of the mould board, because it acts to cut and throw up the dirt as it advances, the rotary movement of the disk reducing the power otherwise required.

In order to secure transverse tilting, and raising and lowering of the circle frame, I suspend it by links 28—29 connected to the arms 30—31. These arms 30—31 are extensions of shafts 32—33, respectively, controlled through worm gearing by the hand operated adjusting wheels 34—35 positioned preferably for operation from the driver's station at the rear of the machine.

Thus by the operation of the wheels 34 and 35 the mould board circle frame may be raised and lowered in horizontal adjustment, or may be tilted transversely in one direction or the other as is found necessary.

I provide a further adjustment of the

mould board suspension apparatus so as to secure a universal adjustment of the same, and to this end provide an additional vertical adjustment of the circle so as to secure a tilting thereof on a transverse axis, preferably the lower suspending points of the links 28 and 29 where they connect to the frame at the eyes 36—37. This tilting is preferably accomplished by an intermediately pivoted draw-bar which connects the mould board suspension with the head 16 and thus directly to the king bolt and king block. This draw-bar extends from the universal connection 38 back of the head 16 through the forked link 39 and pivotally connected at 40 to the bars 41—42 which are fastened to the stationary circle 27. In order to secure this tilting of the circle the draw-bar is connected at its intermediate pivotal point 40 through link 43 with an arm 44 carried by shaft 45. This shaft 45 is connected through worm gear mechanism 46 and shaft 47 to the rear of the machine, where it is operated by the hand wheel 48. Thus as the hand wheel 48 is rotated to the right or left, arm 44 is raised and lowered to tilt the mould board circle frame.

It will thus be seen that the mould board circle frame may be adjusted through the hand wheels 34, 35 and 48 in any direction from a horizontal plane.

Now as to the rotary or circular adjustment of the mould board, any suitable mechanism may be provided, but for this purpose I use a chain 49 secured at its ends to the periphery of the rotatable circle 25 and passing over a sprocket wheel 50 connected through worm gearing 51, shaft 52 and sliding connection 53 to the hand wheel 54 at the rear of the machine. Thus as the hand wheel 54 is rotated to the right or left, the mould board is rotatably adjusted to the desired angle.

As previously stated, a feature of my invention is the transverse adjustment of the mould board suspension whereby, among other things, a wider range of adjustment of the mould board is secured and also a more rigid frame and wheel construction supplied. Furthermore by this transverse adjustment I secure many advantages in, and new methods of, operation of the mould board.

To this end I provide transverse adjusting mechanism including a block 55 slidably carried on the cross bars 56—57 extending from one side rail of the frame to the other. This block 55 has a rearwardly extending arm 58 having a screw 59 passing therethrough and adapted to be rotated through the gearing 60 and hand operated crank 61. Thus as this crank 61 is rotated to the right or to the left the screw 59 is rotated in one direction or the other to slide the block 55 along the ways 56—57. This block 55 is connected to the circle suspension by means of

a link 62 disposed so as not only to adjust the mould board suspension circle transversely of the frame, but also brace it against the strain imposed thereon when the mould board is being drawn against its load.

In connection with that feature of my invention whereby I provide tilting or leveling adjustment of the main frame, this is preferably accomplished in the present illustrated form of my invention by means of hand power supplied by the operator at the rear of the machine.

There are a number of advantages in this feature of my invention when used either alone or in combination with other elements. For instance, it is desirable at many times to maintain the frame on a level although the wheels may be setting on the incline of the road, or one set of wheels on the road and the other in the ditch or a furrow along the road. Also the main frame may thus be tilted to a greater degree than where the ordinary frame is used, thus permitting an adjustment of the mould board to operate in extreme positions, such as for cutting down high banks alongside the road.

Now as to this tilting or leveling mechanism, I preferably support the main frame pivotally at the rear end by the shaft 13 which extends through the block 63 of the rear wheel frame members 64-65. This shaft 13 carries a worm gear 66 at its rear end, operated by a worm 67 on the shaft of the hand crank 68. Thus as the crank 68 is turned in one direction or the other, the main frame is tilted or leveled as desired.

In order to tiltably adjust the wheels of the grader I have provided improved hand operated mechanism whereby the wheels may be more readily adjusted and eliminating the hard work heretofore necessary to effect such adjustment.

In the rear wheel tilting mechanism shown more in detail in Fig. 3, I provide right and left arms 69 pivotally supported at 70 between the rear frame extensions 64-65 and connected through links 71 to the slideable rack 72. The teeth on this rack are engaged by the teeth of pinion 73 carried on a shaft 50 with a worm gear 74 adapted to be rotated by a worm 75 carried on the shaft of crank 76. Thus as the crank 76 is rotated in one direction or the other, the rack 72 is moved to the right or left and the rear wheels tilted to the desired angle.

In the front wheel tilting mechanism, shown more in detail in Figs. 4 and 5, the wheels are supported on right and left axle members 77 connected by links 78 to the rack 79 slidably supported in the front frame 80. This frame turns under the head 16 of the main frame so that the grader may be drawn in the usual manner. In order to operate the wheel inclining rack 79 I preferably employ the operating shaft as the king

bolt or shaft 81 on which the frame 80 turns. This shaft 81 has a pinion 82 at its lower end in mesh with the teeth on rack 79, and has its upper end connected through gearing 83 and shaft 84 to the rear end of the machine where it is operated by the hand wheel 85. Thus as the hand wheel 85 is rotated to the right or to the left, the front wheels are inclined accordingly.

In order to effect adjustment of the tongue 86 for an offset hitch, if desired, this tongue is pivotally attached to the steering frame 87 at 88. The tongue 86 carries a pinion 87 in mesh with the teeth of sector 89 of the steering frame, said pinion 87 being rotated by the worm gear mechanism 90. This latter mechanism is controlled from the operator's platform at the rear of the machine and is connected through a universal joint 91, sliding shafts 92, universal joint 93 and shaft 94 to the hand wheel 95. Thus the operator may rotate the hand wheel 95 to the right or left to adjust the tongue 86, the universal joints 91 and 93 with the sliding connection 92 permitting adjustment of the tongue and operation of the steering frame without interference.

What I claim as new and desire to secure by United States Letters Patent is:

1. In a road grader, front and rear wheel frames, a main frame pivotally supported to its front and rear ends by said wheel frames, a mold board circle frame, means for transversely tilting the main frame and means suspending said circle frame operable to adjust said circle frame tiltably, bodily vertically and transversely of the main frame, said suspending and adjusting means including gear mechanism for all of said adjustments.

2. In a road grader, front and rear wheel frames, a main frame comprising side rails and front and rear end sections each pivotally supported in a corresponding wheel frame, said side rails of the main frame extending forwardly from the rear end and then bending outwardly to widen the frame and then inwardly to a comparatively narrow neck to the front end section, a mold board circle frame positioned beneath the main frame, said main frame being wider at its widened portion than the circle frame, and means for suspending said circle frame from the main frame, said latter means comprising only links extending downwardly inside the rails of the main frame with means carried on the main frame between the outside rails for operating the links to adjust the circle frame.

3. In a road grader, a mold board supporting frame, an intermediately pivoted draw-bar connecting the mold board frame and king block of the grader, and means for raising and lowering the draw-bar at the intermediate pivot to adjust the frame, said

means including a link connected to the intermediate pivot and suspended from an operating lever above for adjusting the link to adjust mold board frame.

5. In a road grader, front and rear wheel frames, a main frame, a mold board and supporting frame therefor, means for adjustably suspending the mold board and supporting frame from the main frame to permit shifting the mold board into different operating positions, and means for adjustably supporting the main frame by the front and rear wheel frames for bodily moving the main frame relative to the front and rear wheel frames to raise and lower the mold board out of and into operating position without necessarily disturbing its adjustment on the main frame.

5. In a road grader, the combination of front and rear wheel frames with tilttable wheels and tilting mechanism therefor, a mold board, and a main frame carrying said mold board transversely tiltably supported in said frames and independently operable tilting mechanism therefor, whereby said wheels may be tilted relative to and independent of their frames and to a vertical plane and the main frame independently tilted relative to the wheel frames and the inclination of the road.

6. In a road grader, front and rear wheel frames, a transversely pivotally tilttable main frame carried by the wheel frames having pivotal supports transversely stationary relative to the wheel frames, and a mold board supporting frame transversely shiftably carried by the main frame.

7. In a road grader, front and rear wheel frames, a transversely pivotally tilttable main frame carried by the wheel frames having pivotal supports transversely stationary relative to the wheel frames, a mold board supporting frame, and means suspending the mold board frame from the main frame operable to transversely shift the mold board frame relative to the main frame and universally adjust it relative to a horizontal plane.

8. In a road grader, the combination of front and rear wheel frames, a leveling main frame carried thereby, a transversely shiftable mold board frame carried by the main frame, and means for tilting the wheels with respect to the same, leveling the main frame and shifting the mold board frame each independent of the other, so as to secure various adjustments of the mold board frame relative to the tread of the wheels.

9. In a road grader, the combination of front and rear wheel frames, a leveling main frame carried thereby, a transversely shiftable and independently vertically adjustable mold board carried by the main frame, and means for tilting the wheels with respect to the same, leveling the main frame and shift-

ing the mold board frame each independent of the other, so as to secure various adjustments of the mold board frame relative to the tread of the wheels.

10. In a road grader, front and rear wheel frames, a transversely tilttable main frame pivotally supported in the wheel frames, a mold board frame transversely adjustably carried by the main frame, a mold board rotatably adjustably carried by the mold board frame, whereby said mold board may be adjusted to substantially parallel to the line of travel of the grader to one side of the grader and the frame tilted to raise the mold board to operate upon high banks.

11. In a road grader, front and rear wheel frames, a main frame transversely tiltably supported by the wheel frames, a mold board circle frame rotatably supported by the main frame, a mold board, means for supporting the mold board on the mold board frame and means for reversing the mold board face relative to the axis of rotation of the circle frame.

12. In a road grader, front and rear wheel frames, a main frame transversely tiltably supported by the wheel frames, a mold board carrying circle frame, and means for supporting the circle frame by the main frame operable to effect bodily transverse, vertical, rotary, and tilting, adjustment of the circle frame independent of tilting adjustment of the main frame.

13. In a road grader, the combination of front and rear wheel frames, a leveling main frame carried thereby, a transversely shiftable mold board frame carried by the main frame, and means for tilting the rear wheels with respect to the rear wheel frame, leveling the main frame and shifting the mold board frame each independent of the other, so as to secure various adjustments of the mold board frame relative to the tread of the wheels.

14. In a road grader, the combination of front and rear wheel frames, a leveling main frame carried thereby, a transversely shiftable and independently vertically adjustable mold board carried by the main frame, and means for tilting the rear wheels with respect to the rear wheel frame, leveling the main frame and shifting the mold board frame each independent of the other, so as to secure various adjustments of the mold board frame relative to the tread of the wheels.

15. In a road grader, front and rear wheel frames, road wheels rotatably supported by said frames, a main frame, a mold board supporting frame, and means for independently transversely tiltably adjusting said main and mold board frames relative to the wheel frames.

16. In a road grader, front and rear wheel frames, a main frame transversely tiltably supported by the wheel frames, a mold board

- supporting frame independently adjustably carried by the main frame, a draw bar for the mold board frame, and means for vertically adjusting the draw bar to raise and lower the same in any angular tilt of the main frame.
17. In a road grader, front wheel frames, tilttable rear wheel frames, a leveling main frame transversely tiltably supported by the front and rear wheel frames, and means whereby the main and tilttable wheel frames may be adjusted to level or tilt the main frame and vertically or tiltably dispose the rear wheel frames, according to the inclination of the road.
18. In a road grader, tilttable front wheel frames, tilttable rear wheel frames, a leveling main frame transversely tiltably supported by the front and rear wheel frames, and means whereby the main and tilttable wheel frames may be adjusted to level or tilt the main frame and vertically or tiltably dispose the front and rear wheel frames, according to the inclination of the road.
19. In a road grader, front and rear wheel frames, a main frame transversely tiltably supported by the wheel frames, a mold board frame independently adjustably supported by the main frame, and a mold board longitudinally adjustably supported by the mold board frame for movement beyond the tread of the wheels on either side with the main frame tilted or leveled.
20. In a road grader, front and rear wheel frames, a main frame transversely tiltably supported by the wheel frames, a mold board supporting frame independently adjustably carried by the main frame, a mold board, and means for reversibly supporting the mold board by said supporting frame to permit adjusting the mold board toward either side of the grader angular to the trend of the road and with the main frame tilted or leveled.
21. In a road grader, front and rear wheel frames, a main frame transversely tiltably supported by the wheel frames, a mold board supporting frame, and means for transversely shiftably suspending the mold board frame from the main frame.
22. In a road grader, a front wheel frame, tilttable rear wheel frames, a main frame supported by the front and rear wheel frames, a mold board frame rotatably supported by the main frame, and a concave operating face mold board reversibly supported by the mold board frame whereby the concave face of the mold board may be positioned toward or away from the axis of rotation of the mold board frame.
23. In a road grader, a main frame, a mold board frame, a pair of crank arms from which said mold board frame is suspended, and means whereby said arms are operable through a complete circle for adjusting the mold board frame.
24. In a road grader, a main frame, a mold board frame, a pair of crank arms from which said mold board frame is suspended, and means whereby said arms are operable through a half circle on one side of a horizontal plane through their axes of rotation for adjusting the mold board frame.
25. In a road grader, a main frame having longitudinal side rails, a mold board frame, a pair of crank arms from which said mold board frame is suspended by links positioned between the side rails of the main frame, and means for mounting said crank arms on the main frame whereby said arms are operable through a complete circle for adjusting the mold board frame.
26. In a road grader, a main frame having longitudinal side rails, a mold board frame, a pair of crank arms from which said mold board frame is suspended by links positioned between the side rails of the main frame, and means for mounting said crank arms on the main frame whereby said arms are operable through a half circle on one side of a horizontal plane through axis of rotation for adjusting the mold board frame.
27. In a road grader, a main frame, a mold board frame, a pair of crank arms transversely rotatable on the main frame and from which said mold board frame is suspended, and means whereby said arms are rotatable through a complete circle to corresponding or different radial positions for adjusting the mold board frame.
28. In a road grader, a main frame, a mold board frame, a pair of crank arms from which said mold board frame is suspended, means whereby said arms are operable through a complete circle for adjusting the mold board frame, and means for transversely shifting the mold board with the crank arms in any angular position.
29. In a road grader, a transversely tiltable main frame, a mold board frame, a pair of crank arms on the main frame from which the mold board is suspended, and means whereby said arms are operable through at least half a circle for adjusting the mold board with the main frame in any of its tilttable positions.
30. In a road grader, front and rear wheel frames, a main frame transversely tiltably supported by the wheel frames, an adjustable mold board supporting frame, and operator controlled adjusting means for the mold board carried by and movable bodily with the main frame.
31. In a road grader, front and rear wheel frames, a main frame transversely tiltably supported by the wheel frames, an adjust-

able mold board supporting frame, operator controlled adjusting means for the mold board carried by and movable bodily with the main frame, and means supported by the rear wheel frame for transversely tilting the main frame.

In witness whereof, I hereunto subscribe my name this 26 day of December, 1923.

DANIEL C. HINDS.
